TICKET PUNCHING DEVICE

Peter Demetrikopoulos, Middle Village, N. Y., assignor to International Electro Ticket Punch Corp., New York, N. Y., a corporation of New York

Application October 16, 1934, Serial No. 748,446

12 Claims. (Cl. 164—86)

This invention relates to ticket punching machines. It is particularly directed to an electrically operated ticket punching machine which may be fixed to a support, for example, a counter or

5 show-case of a cafeteria.

An object of this invention is to provide a device of the character described, which may be readily mounted in handy position for use, for example, on a cafeteria counter, thus eliminating the possibility of injury thereto by dropping, as often results when handling hand punches. The devices being operated electrically, tickets may be rapidly punched, and the device may be used by more than one operator without necessity for

15 shifting position thereof.

Another object of this invention is to provide in a ticket punching device of the character described, a switch controlling the operation of the punch adapted to be actuated by the ticket to be punched, and located close to the punch die so that the ticket is not punched until the same is placed in its position for punching, provision being furthermore made on said device for indicating the point at which the punching takes place to aid the operator in placing the ticket in correct position for punching.

A still further object of the invention is to provide in a device of the character described, a chute for receiving the clippings or the punched out portions of the ticket so that the clippings may be accumulated and emptied at a suitable time, provision being further made to permit observation of the chute so that the operator may know when the chute is substantially full and should be emptied.

Another object of this invention is to provide a device of the character described, including a clamp adapted to engage the edge of a support, for example, the elongated edge of a show-case or counter in a cafeteria, and having an electric socket adapted to receive electric prongs carried by the punching head removably fixed to the clamp, the construction also including an elongated conduit adapted to run along the edge of the show-case or counter and received within said clamp and carrying the electric wires attached to the socket and extending out of the conduit through a suitable opening in the conduit, said construction permitting a number of my improved ticket punching devices to be mounted on the edge of a show-case or counter and receiving electricity for the operation thereof from the wires in the conduit, the conduit having openings at each clamp through which the wires extend for connection to the sockets on the clamps.

Still another object of this invention is to provide in a device of the character described, means to permit the die to be readily removed for replacement.

Yet another object of this invention is to provide a neat, rugged and compact ticket punching device of the character described, which shall be relatively inexpensive to manufacture, simple to install, sanitary in use and withal practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

Fig. 1 is an elevational cross-sectional view of the machine embodying my invention;

Fig. 2 is a side elevational view of the device shown in Fig. 1 in ticket punching position, with parts broken away to show the interior construction;

Fig. 3 is a cross-sectional view taken on line 3—3 of Fig. 1;

Fig. 4 is a cross-sectional view taken on line 4—4 of Fig. 1; and

Fig. 5 is a partial, top plan view of my improved device.

Referring now in detail to the drawing, 50 designates a machine embodying my invention. The machine 50 comprises a case 51 to which there is fixed, in the manner hereinafter explained, a clamp member 52 cooperating with an adjustable clamp member 53 to fix the device to a counter or any other suitable fixed support. The casing 51 may be made of two complementary sections 53a, 54. The casing portion 53a has a bottom wall 55, a top wall 56, a side wall 57 and end walls 59 and 60. The casing portion 54 has a bottom wall 61 aligned with the bottom wall 55, a top wall 62 substantially symmetrical with respect to the wall 56, a side wall 63 parallel to the wall 57 and end walls 64 and 65 aligned with the walls 59 and 60.

Extending upwardly from the wall 56 is an upwardly and inwardly extending wall 67 and extending upwardly from the wall 62 is an upwardly and inwardly extending wall 68 forming with the wall 57 an elongated channel across the top of the casing. The wall 67 is formed with an inclined

edge 69 and a notch 70, for the purpose hereinafter appearing. The wall 68 is likewise formed with an inclined edge 71 aligned with the inclined edge 69 and with a notch 72 aligned with the notch 70. Said wall 68 is furthermore formed with a cut away portion 73, for the purpose hereinafter appearing.

The bottom wall 55 of the casing portion 53a is formed with an opening 75 in one corner thereof and with an upwardly extending chute 76 communicating with said opening. The chute 76 extends upwardly and inclines away from the wall 59 and is formed with an extension received within the cut out portion 73 of the wall 68, said extension being shown at 80. It will be noted that a portion of the wall 59 forms a wall of the chute and a portion of the wall 57 also forms a wall of the chute, said chute, however, extending away from said walls 57 and 59 at the upper portion thereof. The upper portion 80 of the chute is provided with a vertical surface 81 flush with one edge of the aligned slots 70, 72, and also with an opening 82 adjacent said slot. Received within the opening 82 is a punch die 83 fitted within said opening by friction. The rear wall 84 of the chute is provided with a screw threaded opening 85 aligned with the opening 82 and receiving a screw plug 86, which may be removed to permit insertion of the tool for removing the die 83.

It will be noted that the ticket 88 may be inserted into the slots 70, 72 and against the surface 81 and the die 83 in position for punching, the inclined surfaces 69 and 71 serving as a guide in inserting the ticket to punching position.

The casing portions 53a, 54 may be attached together by a plurality of bolts 90 extending through bosses 91 integrally formed with said casing portions.

For the purpose hereinafter appearing, the end wall 64 is formed with an inwardly extending flange 92 forming an opening 93, for the purpose hereinafter appearing. Said wall 64 is furthermore formed at the top and bottom thereof with rearwardly extending perforated ears or lugs 95 and 96. One wall, 76a, of the chute 76 is formed with an extension 100 formed with a through opening 101 extending through the wall 57 of the casing portion 53. Extending through said opening is a screw 102 having a pin portion 104 extending beyond the chute. Mounted on said pin portion 104 is a lever 105 retained on said pin portion by a nut 107 screwed to said portion. The lever 105 is provided with an upwardly extending arm 108 having a punch 109 adapted to be received within the die 83 for punching the ticket 88 inserted into the slots 70, 72. Said lever 105 is also provided with a downwardly extending arm 110 to which there is fixed an armature 111. A coil tension spring 113 attached at one end to a pin 114 fixed to the casing portion 63 and at the other end thereof to the arm 108 of the lever 105, serves to rotate the lever in a clockwise direction to remove the punch 109 from the die 83. Cooperating with the armature 111 of the punch lever 105 are a pair of electromagnets 116 and 117 fixed to the walls 60 and 65 of the casing portions 53a and 54, respectively.

Upon energizing the electro-magnets in the manner hereinafter appearing, the armature 111 is actuated toward the cores of the magnets to swing the lever 105 against the tension of spring 113 for punching the ticket.

Fixed to the arm 108 of the lever 105 is a screw 108a. The bottom end of the surface 81 of por-

tion 80 of the chute is formed with a groove 81a receiving a felt strip or washer 81b. Upon energizing the electro-magnets 116 and 117 for causing swinging movement of the lever 105, the screw 108a will contact the felt pad or washer 81b which acts as a shock absorber to prevent the armature 111 from striking the cores of the magnets. As shown in Fig. 2 of the drawing, the armatures are somewhat spaced from the cores when the lever 105 is in ticket punching position.

It will be noted that the upper edges of the fibre plates 122 and 123 traverse the slots 70 and 72 and are located on opposite sides of the opening in the die 83. The switch 130 thus cannot be closed except when the ticket is inserted into the slot and moved down into punching position. The switch is thus not exposed for actuation except when the ticket is moved to ticket punching position. The slots 70, 72 are too small for the insertion of a finger and the likelihood of the punch being actuated before the ticket is in proper position is minimized.

Means is provided for closing the circuit through the electro-magnets to energize the same upon inserting the tickets 88 in position for punching. To this end, there is fixed on the opposite walls 67, 68 a transverse pin 120 on which is pivoted a block 121 to the opposite faces of which there are fixed a pair of parallel plates 122 and 123 made of fibre or other insulating material.

The casing portion 54 is formed on the inner surface thereof at the corner formed between the walls 62 and 63, with a projection 125 to which there is screwed a pin 126. Pivoted on said pin 126 is a switch lever 127 having parallel ears 128 receiving said pin therethrough. One end of the lever 127 contacts, as at 129, an edge of the fibre plate 122. Fixed to the opposite end of the lever 127 is a mercury switch 130 of well known construction. Received on the pin 126 and between the ears 128 is a torsion spring 131 normally tending to rotate the lever 127 in a clockwise direction, looking at Fig. 9 of the drawing, to rotate the block 121 in a clockwise direction about the pivot 120.

Received within the opening 93 of the tubular flange 92 is an electric plug fitting 133 provided with a pair of parallel projecting plug blades 134. Attached to the blades 134 are wires 136 and 137 connected to the electro-magnets 116 and 117 and having interposed therein the mercury switch 130. As described hereinafter, the blades 134 may be attached to a socket 138 leading to a source of electric power to supply electricity to the magnets 116 and 117.

It will now be understood that upon inserting the ticket 88 within the slots 70, 72, the fibre plates 122 and 123 are engaged by the lower edge 60 of the ticket and the block 121 rotated in a counter-clockwise direction for depressing one end of the lever 127 to rotate the latter likewise in a counter-clockwise direction to close the switch 130. Upon the switch being closed the circuit is completed through the electro-magnets and the armature is attracted by the electro-magnets and causes the lever 105 to swing in a counter-clockwise direction against the tension of the spring 113 to punch a notch 140 in the lower edge of the ticket 88.

Upon the ticket being removed, the torsion spring 131 causes a clockwise swinging movement of the lever 127 to lift the fibre plates 122, 123. During this movement of the lever 127 the

switch 130 is swung to open position to break the circuit through the electromagnets whereby the armature 111 is released and the spring 113 rotates the lever 105 in a clockwise direction to the position shown in Fig. 1 of the drawing.

5 The side wall 57 of the casing portion 53 is formed with a window 142 adjacent the top of the chute 16. The opening 75 at the bottom of the chute is closed by a plate 143 screwed to the bottom wall 55, as by screw 144, whereby the pieces punched from the ticket 88 are collected within the chute and through the window 142 it may be observed when the pieces of tickets within the chute substantially fill the chute, to 10 warn the operator to remove the plate 143 and empty the chute of ticket pieces. The plate 143 may be swung about the screw 144 in a horizontal plane to uncover the opening 75. It will thus be noted that the chute may be emptied without 15 removing the machine from its support.

20 Means is provided for clamping the casing 53 to any suitable support, for example, the edge of a counter in a cafeteria. To this end, there is attached to the casing 50 the member 52 which 25 comprises a casting having a wall 150 contacting the wall 64 and formed with a tubular portion 151 aligned with the tubular portion 92. Extending from the wall 150 is a rearwardly extending horizontal wall 153 from which there projects upwardly a pair of parallel perforated ears 30 or lugs 154 receiving therebetween the lug 95. At the bottom end thereof the member 52 is provided with a horizontal wall 155 and a pair of parallel perforated ears or lugs 157 receiving 35 therebetween the lug 96. The lugs or ears 95 and 96 are attached to the lugs 154 and 157 by bolts 158 and 159, respectively.

40 Associated with the member 52 is the movable clamping member 53 which comprises a casting having a rear, vertical wall 160, parallel side walls 161, a bottom wall 162 and a top wall 163. Extending upwardly from the wall 163 are a pair 45 of parallel, spaced, aligned, vertical walls 165 formed with shoulders 166. Extending through screw threaded openings 155a in the bottom wall 155 of member 52 are a pair of vertical screws 170, the upper ends of which are received in sockets 171 in the bottom wall 162 of member 53. Received on the shoulder 166 and contacting the walls 165 and the undersurface of the wall 153, is a tubular member 175 receiving therethrough a duplex wire 176. The member 175 may be of rectangular cross-section and the bottom thereof is formed with a cut out portion 50 55 177 through which the duplex cable 176 extends, said cable passing between the spaced walls 165 and extending into the chamber 178 formed by member 53. Attached across the wires 176 in parallel is the electric socket 138 received within 60 the tubular member 175 and receiving the plug blades 134.

65 The screws 170 may be employed for adjusting the vertical position of the member 53 to raise or lower the same for clamping the machine to the edge of a counter or other support inserted between the walls 163 and 153. A number of machines 50 may be mounted on the edge of a counter in spaced relation, the wires 176 being tapped at spaced points for supplying 70 electricity to the machines.

75 It will be noted that the casings 50 may be removed from the clamps by merely withdrawing the bolts 158 and 159 and without disturbing the clamps 52, 53.

75 The top surface of the wall 68 may be provided

with an arrow 16a or other mark, pointing to the middle of the die 83 to indicate the exact point at which the punching will take place. The operator is thus guided in applying the ticket so that the desired number may be punched. The 5 plates 122, 123 may be made of metal or any other suitable material.

10 It will be understood that a number of machines 50 may be mounted on a single elongated counter and one duplex cable 176 extending 10 through an elongated conduit 175 may serve to supply electric current to all the machines, the conduit 175 being formed with cut out portions 177 at spaced intervals, to permit the duplex wires to pass out of the conduit for attachment 15 to the sockets 138.

15 It will thus be seen that there is provided a device in which the several objects of this invention are achieved, and which is well adapted to meet the conditions of practical use. 20

25 As various possible embodiments might be made of the above invention, and as various changes might be made in the embodiments set forth, it is to be understood that all matter herein contained, or shown in the accompanying 25 drawing, is to be interpreted as illustrative and not in a limiting sense.

30 Having thus described my invention, I claim as new and desire to secure by Letters Patent:

35 1. A ticket punch comprising a casing, a lever pivoted therein and having an armature at one end, an electro-magnet within the casing for attracting said armature, a punch on said lever, a chute within said casing having a die on a wall thereof adapted to receive said punch, spring means for rotating said lever, a tilting switch pivoted within said casing, and means for tilting said switch comprising a member pivoted within said casing and adapted to be rotated about its axis by a ticket placed in punching position adjacent said die. 40

45 2. A ticket punch comprising a casing formed with a slot, electric means within said casing for punching a ticket inserted within said slot, and means for actuating said means, including a pivoted member traversing said slot and adapted to be rotated about its axis by the ticket upon inserting the same into said slot, said electric means including a pivoted tilting switch normally open and adapted to be tilted into closing position upon rotating said pivoted member by inserting said ticket into said slot. 50

55 3. A ticket punching machine comprising a casing, a punch and die therein, electric means in said casing for actuating said punch, a vertical chute in said casing associated with said die to receive the clippings, a wall of said chute constituting a part of said casing, and window means on said wall of said chute adjacent the upper end of said chute to permit observation of the inside of the chute from the outside of said casing, and a removable closure at the bottom of said chute to permit removal of the accumulated clippings from said chute. 60

65 4. In combination, a casing, electric means within said casing, means for fixing the casing to a support comprising a clamping member fixed to said casing, a conduit adapted to be fixed to said support by said clamp, and electric wires extending through said conduit and connected to 70 electric means.

75 5. In combination with an elongated support having an edge, an elongated conduit disposed against said edge, means for clamping said conduit to said support, an electric fitting on said 75

- clamping means, said conduit having an opening, electric wires extending through said conduit, and opening, and being attached to said fitting, and an electric ticket punching device
- 5 comprising a casing fixed to said clamping means and having an electric fitting thereon complementary to said first electric fitting and being adapted to engage the same upon fixing said casing to said clamping means, electric means within said casing for punching a ticket including an electro-magnet, the coil whereof is connected to said second fitting.
- 6 In combination with an elongated support having an edge, an elongated conduit disposed alongside said edge, a ticket punching device fixed to the edge of said support, and including means to clamp said conduit to said edge of said support, electric wires within said conduit, said ticket punching device including electric means for operating a punch, and said wires passing out of said conduit for supplying electricity to said electric means.
7. A ticket punching device comprising a casing, an electro-magnet within the casing, a member pivoted within said casing and having an armature at one end adapted to be attracted by said electro-magnet, a punch at the upper end of said pivoted member, said casing being formed with a slot adapted to receive a ticket to be punched and having a die registering with said slot, said punch being adapted to move across said slot and into said die, and means for closing the circuit of said electro-magnet including a second pivoted member within the casing and traversing said slot, and a tilting switch likewise pivoted within the casing and contacted by one end of said second pivoted member, said second pivoted member being adapted to be rotated upon inserting a ticket to be punched, into said slot, 40 for tilting said switch.
8. A ticket punch comprising a casing, a lever pivoted therein and having an armature at one end, an electro-magnet within the casing for attracting said armature, a punch on said lever, a chute within said casing having a die on a wall thereof adapted to receive said punch, spring means for rotating said lever, a tilting switch pivoted within said casing, and means for tilting said switch comprising a member pivoted within 45 said casing and adapted to be rotated about its axis by a ticket placed in punching position adjacent said die, said pivoted member having portions disposed on opposite sides of the die and adjacent thereto.
- 50 9. A ticket punch comprising a casing, an electro-magnet within the casing, a lever pivoted within the casing and having an armature at one end adapted to be attracted by said electro-magnet for rotating said lever, a punch on said lever, a chute within said casing having a die on the wall thereof, said casing being formed with a slot adapted to receive a ticket to be punched, said slot registering with said die, a member pivoted to the casing at one end thereof and having a portion traversing said slot, a tilting switch pivoted within the casing and having an extension engaging the opposite end of said pivoted member, whereby rotation of said pivoted member about its axis, caused by a ticket 55 inserted into the slot, will cause rotation of said tilting switch in one direction, spring means for rotating the tilting switch in the opposite direction and for moving said pivoted member back to normal position when the ticket is removed from said slot, and means for energizing said electro-magnet
- 60 10. A ticket punch comprising a casing, an electro-magnet within the casing, a lever pivoted within the casing and having an armature at one end adapted to be attracted by said electro-magnet for rotating said lever, a punch on said lever, a chute within said casing having a die on the wall thereof, said casing being formed with a slot adapted to receive a ticket to be punched, said slot registering with said die, a member pivoted to the casing at one end thereof and having a portion traversing said slot, a tilting switch pivoted within the casing and having an extension engaging the opposite end of said pivoted member, whereby rotation of said pivoted member about its axis, caused by a ticket inserted into the slot, will cause rotation of said tilting switch in one direction, spring means for rotating the tilt- 65
- 65 11. A ticket punch comprising a casing, an electro-magnet within the casing, a lever pivoted within the casing and having an armature at one end adapted to be attracted by said electro-magnet for rotating said lever, a punch on said lever, a chute within said casing having a die on the wall thereof, said casing being formed with a slot adapted to receive a ticket to be punched, said slot registering with said die, a member pivoted to the casing at one end thereof and having a portion traversing said slot, a tilting switch pivoted within the casing and having an extension engaging the opposite end of said pivoted member whereby rotation of said pivoted member about its axis, caused by a ticket inserted into the slot, will cause rotation of said tilting switch in one direction, spring means for rotating the tilting switch in the opposite direction and for moving said pivoted member back to normal position when the ticket is removed from said slot, means for energizing said electro-magnet upon tilting said switch for attracting said armature and causing the punch on said lever to punch said ticket, said chute having a screw-threaded opening aligned with said die and a screw block removably screwed into said screw-threaded opening. 70
- 70 12. A ticket punch comprising a casing, an electro-magnet within the casing, a lever pivoted within the casing and having an armature at one end adapted to be attracted by said electro-magnet for rotating said lever, a punch on said lever, a chute within said casing having a die on the wall thereof, said casing being formed with a slot adapted to receive a ticket to be punched, said slot registering with said die, a member pivoted to the casing at one end thereof and having a portion traversing said slot, a tilting switch pivoted within the casing and having an extension engaging the opposite end of said pivoted member, whereby rotation of said pivoted member about its axis, caused by a ticket inserted into the slot, will cause rotation of said tilting switch in one direction, spring means for rotating the tilt- 75

ing switch in the opposite direction and for moving said pivoted member back to normal position when the ticket is removed from said slot, means for energizing said electro-magnet upon tilting said switch for attracting said armature and causing the punch on said lever to punch said ticket, said chute having a screw-threaded opening aligned with said die, a screw block removably

screwed into said screw-threaded opening, indicating means on said casing to indicate the point at which the punching takes place, and shock absorbing means to limit rotary movement of said lever to prevent said armature from striking said electro-magnet. 5

PETER DEMETRAKOPoulos.
